CASKET

Jeanne Christine M. Soden, Ute Park, N. Mex.

Application May 23, 1950, Serial No. 10,126

Term of patent 14 years

(Cl. D19—1)

To all whom it may concern:

Be it known that I, Jeanne Christine M. Soden, a citizen of the United States of America, residing at Ute Park, county of Colfax, and State of New Mexico, have invented a new, original, and ornamental Design for a Casket, of which the following is a specification, reference being had to the accompanying drawing, forming a part thereof wherein:

Figure 1 is a view in side elevation of a casket with the lid thereof opened, showing my new design;

Figure 2 is a top plan view of the casket with the lid in opened position;

Figure 3 is a view in end elevation of the casket with the lid opened and looking at the head end of the casket, and

Figure 4 is a view in end elevation of the casket with the lid opened and looking at the foot of the casket.

I claim:

The ornamental design for a casket, as shown.
JEANNE CHRISTINE M. SODEN.
